CLAIM

The ornamental design for a plastic container as shown and described.

DESCRIPTION

FIG. 1 is an elevation view of a plastic container.

FIG. 2 is an elevation view of the plastic container.

FIG. 3 is an elevation view of the plastic container.

FIG. 4 is an elevation view of the plastic container.

FIG. 5 is a top plan view of the plastic container.

FIG. 6 is a bottom plan view of the plastic container.

FIG. 7 is a perspective view of the plastic container.

FIG. 8 is a perspective view of the plastic container.

FIG. 9 is a perspective view of the plastic container.

FIG. 10 is a perspective view of the plastic container.

FIG. 11 is a perspective view of the plastic container.

FIG. 12 is a perspective view of the plastic container.

FIG. 13 is a perspective view of the plastic container.

FIG. 14 is a perspective view of the plastic container.

FIG. 15 is a perspective view of the plastic container.

FIG. 16 is a perspective view of the plastic container.

FIG. 17 is a perspective view of the plastic container.

FIG. 18 is a perspective view of the plastic container.

FIG. 19 is a perspective view of the plastic container.

FIG. 20 is a perspective view of the plastic container.

FIG. 21 is a perspective view of the plastic container.

FIG. 22 is a perspective view of the plastic container.

FIG. 23 is a perspective view of the plastic container.

FIG. 24 is a perspective view of the plastic container.

FIG. 25 is a perspective view of the plastic container.

FIG. 26 is a perspective view of the plastic container; and,

FIG. 27 is a perspective view of the plastic container.
